C. A. Snow & Co.

UNITED STATES PATENT OFFICE.

JOSIAH R. MASTERS, OF JOHNSONVILLE, NEW YORK.

OSCILLATING BED-SPRING.

SPECIFICATION forming part of Letters Patent No. 357,215, dated February 8, 1887.

Application filed June 29, 1886. Serial No. 206,634. (No model.)

To all whom it may concern:

Be it known that I, JOSIAH R. MASTERS, a citizen of the United States, residing at Johnsonville, in the county of Rensselaer and State 5 of New York, have invented a new and useful Improvement in Bed-Bottoms, of which the following is a specification.

This invention relates to a spring-frame, which is designed to be applied to the ordinary 10 or any suitable form of bedstead, and the invention more particularly relates to that class of spring-frames which are shown and described in my former patent, No. 257,879, dated May 16, 1882.

15 The object of the invention is to cheapen and strengthen the construction of this class of devices and to avoid the defects incident to the use of wood employed in the device referred to as embraced in my said patent.

20 To the above purposes my invention consists in certain peculiar and novel features of construction and arrangement, as hereinafter described and claimed.

25 In order that my invention may be fully understood, I will proceed to describe it with reference to the accompanying drawings, in which—

Figure 1 is a plan view of my improved 30 spring-frame applied to a bedstead. Fig. 2 is a longitudinal vertical section of the same on the line $\alpha\alpha$ of Fig. 1. Fig. 3 is a transverse vertical section of the same on the line yy of Fig. 1. Fig. 4 illustrates certain details of construction, hereinafter referred to.

35 A designates the springs or spring-slats forming the body of the device, and B B designate the end bars, to which said springs are connected, in the manner hereinafter described. Each of these end bars, B, is composed of a central tubular section, b, which is 40 to be of varying lengths, according to the width, or size of bedsteads to which the device is to be applied.

45 C designates longitudinal arms, which are coupled to the ends of the central tubular section, b, by a tubular T-section, c. Beyond these tubular T-sections c extend tubular sections b', forming continuations of the end bars. It 50 will thus be seen that the end bars are tubular throughout, and that they may be made of greater or less length, as desired. Each pair of arms C are connected at their rear ends by

a cross-bar, D, and said arms C extend upward above the level of the end bars, B, at their outer ends, so that the cross-bars D lie above 55 the level of said end bars and strain upward upon the springs A. To each end of each of the end bars, B, is inserted an extension, E, carrying upon its outer end the bracket F, similar to that described in my former patent, No. 65 257,879, and the portion of the extension within the end bars is impinged upon by a set-screw, e, in such manner as to hold the extension at any desired point of adjustment within the end bar. It will thus be seen that these 65 extensions serve to further extend the end bars, and also to more readily contract their length than could be done by removing the sections b'.

Ratchet-plates G are secured upon the inner 70 sides of the bedstead-frame, and the teeth of said ratchet-frame are engaged by an arm, g, in the manner described in my said former patent. The ends of the springs A are bent under and over the end bars, B, and their extremities are turned in upon slots b², formed on the inner faces of the end bars. Thus no pins or bolts are required to fasten the springs to the end bars, and the springs are more 75 readily attached to and removed from said end bars than would otherwise be the case.

The operation of this structure is essentially the same as that described in my former patent, previously alluded to. When the brackets are set lower down upon the ratchet-plates, 85 the springs are strained and the bottom of the bed is made more rigid than when the brackets are adjusted to the upper part of the ratchet-plate, and consequently the sustaining-power of the bed-bottom may be readily varied to 90 suit heavier or lighter persons.

In lieu of the brackets F, the ends of the extensions E may be provided with T-shaped heads, by which the spring-frame is suspended from the bedstead-frame, in which case the 95 ratchet-plates may be dispensed with.

Having thus described my invention, I claim—

1. The herein-described improved bed-bottom, consisting of the extensible end bars, B, 100 having the arms C and cross-bars D, and the springs A, connected to the said end bars, substantially as described.

2. The combination, with the tubular ex-

tensible end bars, the longitudinal arms, and the cross-bars, of the springs A, suitably connected to said tubular end bars, and the extensions E, and means for connecting said extensions with the bedstead-frame, substantially as described.

3. The combination, with the tubular end bars, composed of the central section, b, T-sections c, and tubular extension b', of the springs A, having their ends inserted in the slots in said end bars, the longitudinal arms C, connecting the cross-bars D and inserted into the T-sections c, and suitable means for connecting the spring-bottom with the bedstead-frame, substantially as described.

4. The combination, with the tubular extensible end bars and the extensions E, of the ratchet-plates connected to the bedstead-frame, the arms C, and the cross-bars D, substantially as described.

In testimony that I claim the foregoing as my own I have hereto affixed my signature in presence of two witnesses.

JOSIAH R. MASTERS.
